UNITED STATES PATENT OFFICE.

JOSEPH L. WELLS, OF PHILADELPHIA, PENNSYLVANIA, ASSIGNOR TO THE
WESTON & WELLS MANUFACTURING COMPANY, OF CAMDEN, N. J.

BRAIDED-WIRE TUBULAR SPRING.

SPECIFICATION forming part of Letters Patent No. 339,954, dated April 13, 1886.

Application filed April 9, 1885. Serial No. 161,752. (No model.)

To all whom it may concern:

Be it known that I, JOSEPH L. WELLS, a citizen of the United States, residing at the city and county of Philadelphia, and State of Pennsylvania, have invented certain new and useful Improvements in Braided-Wire Tubular Springs, of which the following is a full, clear, and exact description, reference being had to the accompanying drawings.

10 Figure 1 is a perspective view of my invention. Fig. 2 is a plan view of the core or former upon which the wires of which the spring is constructed are braided. Fig. 3 is a side elevation of said core.

15 This invention relates to that class of springs for furniture, car-seats, cushions, pillows, mattresses, and other uses which are constructed of elastic steel or other wire interbraided or interwoven by a suitable machine 20 into tubular form. Examples of such tubular interbraided springs are described in the specification and shown in Figs. 3, 4, and 16 in Letters Patent No. 225,754, granted to Nicholas Jenkins, March 23, 1880; also in Letters Patent No. 264,007, granted to Henry Weston, 25 September 5, 1882.

The invention relates particularly to such springs where the compression to which they are to be or may be subjected is in a transverse instead of a longitudinal direction—as, for example, in cushions, pillows, &c.

30 The improvement consists in braiding or forming the spring in the shape of an arch—that is to say, a tube flattened on one side—35 whereby certain advantages result, as herein-after explained.

Referring to the drawings, Figs. 1 and 2 represent a core or former upon which the steel wires are interlaced by a suitable braiding-machine. It will be observed that this core 40 is circular in cross-section, except that it is flattened on one side at *a*. This form is of course imparted to the tubular fabric, which is made continuously, as described in an application for Letters Patent executed by me the 17th 45 day of February, 1885, for an improvement in wire-braiding machines. The fabric is cut off into desired lengths—such as that shown in Fig. 1, in which *b* marks the interbraided wires; *c*, the arched or circular part of the tube, 50 and *d* the flattened portion.

The advantage of this form over the usual circular or oval springs of the class mentioned is that by means of the single arch, in lieu of the double arch, a greater resistance is presented to the pressure upon the top of the spring, and consequently I am enabled to use a much lighter wire than is necessary in the said double-arch springs.

Having thus described my invention, I claim 60 as new and desire to secure by Letters Patent—

As a new article of manufacture, a tubular interwoven or braided wire spring flattened on one side, substantially as and for the purpose set forth.

65 In testimony whereof I have hereunto affixed my signature this 25th day of February, A. D. 1885.

JOSEPH L. WELLS.
